Fig. 3

Fig. 4

Fig. 5

Fig. 6

FIGURE 1 is a perspective view of a necklace clasp, showing my new design;

FIGURE 2 is a bottom plan view thereof;

FIGURE 3 is an end elevational view as taken from the left hand end of FIGURE 1;

FIGURE 4 is a side elevational view thereof, the opposite side being the obverse of that shown;

FIGURE 5 is an end elevational view as taken from the left hand end of FIGURE 4; and

FIGURE 6 is a top plan view thereof.

I claim:

The ornamental design for a necklace clasp, as shown and described.
